UNITED STATES PATENT OFFICE.

GEORGE A. WIECHERT, OF NEW YORK, N. Y.

ROTARY CASTING DEVICE.

Application filed December 30, 1921. Serial No. 525,858.

To all whom it may concern:

Be it known that I, GEORGE A. WIECHERT, a citizen of the United States, residing in the city of New York, borough of Queens, 5 Howard Beach, in the county of Queens and State of New York, have invented a new and Improved Rotary Casting Device, of which the following is a full, clear, and exact description.

10 My invention relates to rotary casting devices; that is, to casting devices in which centrifugal force is used for the purpose of driving molten metal or the like into a molding flask.

15 My invention contemplates a number of distinct objects, among which are the following:

I. To so arrange and form a molding flask and a crucible for discharging molten metal 20 therein that the crucible, containing the molten metal, extends partly into the molding flask and into very close proximity to the molding cavity into which the molten metal is to be driven by aid of centrifugal force.

25 II. To produce a centrifugal casting device provided with a centrifugal arm for supporting the molding flask, and further provided with positively operating mechanism for locking the centrifugal arm so as 30 to prevent it from turning accidentally and also to prevent said arm from becoming locked accidentally.

III. To provide an improved molding flask and an improved molding sprue, for 35 use upon centrifugal casting devices.

IV. To provide improved mechanism for securing the molding flask and parts immediately associated therewith upon the revol- 40 uble casting arm, and for releasing the same therefrom.

V. To provide a rotary casting device 45 having its parts so constructed and arranged as to attain for the device as a whole a relatively high degree of efficiency, both in the saving of time and in the quality of the articles cast.

Reference is made to the accompanying drawings forming a part of this specification, and in which like reference characters 50 indicate like parts throughout the several figures.

Figure 1 is a side view of my rotary casting device, and shows the same as partly in elevation and partly broken away.

Figure 2 is a plan view of the rotary cast- 55 ing device appearing in Figure 1.

Figure 3 is a fragmentary vertical section through the upper portion of the same.

Figure 4 is a fragmentary edge view of my device, showing the same as partly in eleva- 60 tion and as partly broken away.

Figure 5 is a side view of a revoluble arm and parts immediately associated therewith, the view being partly in side elevation and partly broken away. 65

Figure 6 is a side elevation of a yoke used for holding the molding flask and crucible upon the centrifugal arm.

Figure 7 is a plan view of the yoke shown in Figure 6. 70

Figure 8 is a plan view of the sprue used in connection with my device.

Figure 9 is a side view of the sprue, showing it as partly in elevation and as partly broken away. 75

Figure 10 is a plan view of the molding flask in which the casting is made.

A table 17 supports a casing 18, the latter being provided with a flange 19 extending vertically downward and abutting the edge 80 of the table. For the purpose of holding the casing firmly in position I use bolts 20, extending through feet 21, carried by the casing and in this instance integral therewith. 85

Located within the casing 18 is a gear 22, which engages a pinion 23, also located within the casing. The gear 22 is mounted rigidly upon and carried by a revoluble shaft 24, this shaft extending through the 90 casing and being journaled thereto.

Mounted rigidly upon one end of the shaft 24 is a block 25. Extending from this block is an arm 26, connected with the block by means of a pivot pin 27, as may be understood from Figure 5. The arm 26, at its outer or free end, carries a handle 28. The arm 26 is movable relatively to the block 25 to a slight extent. That is to say, it is so mounted upon the block that it may be 100 moved into the positions indicated for it in Figures 3 and 4 respectively.

The block 25 is provided with a notch 29, and the arm 26 carries a leaf spring 30, provided with a portion 31 bent laterally to the 105 length of the leaf spring, and thus formed into a hook, as may be understood from Figure 4. The leaf spring 30 is secured to

the arm 26 by fastenings 32; in this instance screws.

Mounted upon the arm 26 is a small bearing 33, of the form shown more particularly in Figures 3, 4 and 5. Extending through this bearing, and journaled thereto, is a small crank 34, provided with a handle 35 and with an upturned portion 36, serving as a cam.

10 The arm 26 carries a lug 38, and the casting 18 is provided with a slot 39 into which this lug is adapted to fit, as indicated in Figure 4.

The block 25 carries a leaf spring 37, 15 which extends over the leaf spring 30 and engages and presses upon the outer or free end of the arm 36. The leaf spring 37 is for the purpose of forcing the arm 26 into such position as to enable the lug 38 to enter the slot 39, and thus lock the arm against rotation.

With the lug 38 extending into the slot 39, as indicated in Figure 4, the arm 26 and parts connected therewith cannot be turned 25 so as to cause the gear 22 to rotate. With the arm 26 rocked into the position indicated for it in Figure 3, however, so that the lug 38 is removed from the slot 39, the arm 26 can be turned so as to cause the 30 gear 22 to rotate.

The tension of the leaf spring 30 is such, and the various parts are so proportioned and arranged, that the handle 28 may be grasped and pulled to the left according to 35 Figures 3 and 4, thus causing the portion 31 of the leaf spring 30 to slip into the notch 29, so that the parts appear as indicated in Figure 3. Whenever this occurs, the lug 38 can not enter the slot 39, even if considerable pressure be exerted against the handle 40 28 or against the arm 26. The reason is, that the portion 31 of the leaf spring serves as an anchor for preventing the arm 26 from swinging to the right according to 45 Figure 3.

Whenever the parts occupy the positions indicated for them in this figure, the operator may grasp the handle 28, and by revolving it bodily around the shaft 24 as a center, can freely turn the gear 22 and the parts driven thereby. While this is being done, and even if the handle 28 be given a considerable number of turns at either a high speed or a low speed, there is no possibility 55 of the lug 38 extending into the slot 39.

The purpose of this arrangement is to prevent all interference, for the time being, with the free rotation of the gear 22 and the parts used for driving the same. 60 In other words this arrangement prevents the possibility of a sudden stoppage of the revoluble parts due to the lug 38 slipping into slot 39. Except for this provision the lug 38, by entering the slot 39 at an unexpected moment, might cause breakage, dis-

location or severe shock to some one or more of the revoluble parts.

The purpose of the crank 34, with its upturned portion 36 and handle 35, is to enable the operator to readily force the leaf spring 70 30 away from the arm 26, in order to disengage the portion 31 of the leaf spring from the notch 29. The operator, by grasping the handle 35 and slightly rocking the crank 34, causes the cam 36 to act upon the leaf spring 30 and actuate it in the manner just stated. It follows that after each use of the machine during which the gear 22 is rotated, the operator by shifting the position of the handle 35 of the crank 34, and turning the handle 28 80 so as to allow the lug 38 to enter the slot 39 as elsewhere described, can leave the machine in such condition that its revoluble parts are locked against rotation.

The net result is that at all times except 85 when the revoluble parts are in motion, they are firmly locked against rotation; and when they are in proper condition for rotation they cannot become accidentally locked.

The arrangement just described tends 90 therefore to prevent accidents of a certain kind, and renders the apparatus "fool proof."

The pinion 23 is rigidly mounted upon a 95 shaft 40, the latter being journaled to the casing as may be understood from Figures 1 and 2.

The shaft 40 carries a sleeve 41, which is rigid upon and revoluble with it.

Extending diametrically through the 100 sleeve 41 is a centrifugal arm 42, and mounted upon one end of this arm is a counterweight 43.

The flask used for molding appears at 44, 105 and is provided with an anchoring rib 45, this rib having a cross section of the form of a cross, as may be understood from Figure 10. In order to mount the flask 44 upon the centrifugal arm 42 I provide a yoke 46, having the form indicated in Figures 6 and 7. 110

This yoke is provided with a pair of blades 48, extending parallel with each other and separated by a slot 49, as indicated in Figure 7. The yoke 46 carries a pin 50, and mounted upon this pin is a hook 51, provided with a handle 52, integral with it. The anchoring rib 45 of the flask 44 is provided with a hole 51^a, so located and arranged that the hook 51 may be thrust through it or withdrawn from it whenever the flask is in proper position upon the centrifugal arm 42 and the handle 52 is actuated for the purpose. 115

The yoke 46 is provided with a massive collar 47, which is shrunk upon or otherwise tightly secured to the centrifugal arm 42, as may be understood from Figure 16. With the yoke 46 in position upon the centrifugal arm 42, the flask 44 may be placed upon the yoke 46 and there locked in 120 position. For this purpose the anchor- 125

ing rib 45 is first brought into alinement with the slot 49, and then the flask is slid telescopically upon the yoke until it reaches the limit of its travel relatively thereto. This 5 brings it into such position that the hook 51 may be thrust through the hole 51^a by a movement of the handle 52, as above described. The yoke 46 is provided with a shoulder 46^a, shown more particularly in Figures 7 and 16, and against which the adjacent edge of the flask 44 is adapted to abut, as indicated in Figure 16. The yoke 46 is further provided with a flange 46^b, integral with it and having a general arcuate 15 form, as indicated in Figures 6 and 7. This flange 46^b is for the purpose of holding a crucible, as hereinafter described.

Associated with the flask 44 is a sprue plate 53, having in this instance the form of a metallic plate. The sprue plate is provided with an indentation 54 substantially of semi-cylindrical form as may be understood from Figures 8 and 9. The purpose of the indentation 54 is to form an indentation in 20 the filling to be contained in the flask, for a purpose hereinafter set forth. The sprue plate is further provided a portion 55 extending laterally and having the form of a blade. The sprue plate is further provided 25 with air holes 56, anchor lugs 57, and concave edge portions 58, so positioned as to serve as auxiliary air vents.

The flask 44 is provided with anchor notches 59, as shown in Figure 10. These 30 are for the purpose of receiving the anchor lugs 57 whenever the sprue is fitted upon the flask 44.

The filling is shown at 65 in Figure 13 and has a form which may be understood 40 from said figure, the various voids being shown at 66, 67, 68 and 69, and communicating with each other. The void 66 constitutes a mold cavity, in which the casting is to be formed. The void 67 is merely a passage 45 left by some one of the wax threads 63, and now adapted to serve as a vent hole, for permitting the escape of air from the lower portion of the flask, as the molten metal is poured into the mold. The void 69 is of 50 proper form to serve as an ingate. The void 68 has a semi-cylindrical form, and is thus adapted to receive the edge of a crucible 70 of the form indicated in Figure 16. This crucible has a relatively thick bottom, as 55 shown in Figure 16, and is provided with a compartment 71 for holding the metal to be melted and used in casting.

The operation of my device may be readily understood from the foregoing description—

For purposes of casting the first step is to mount the flask and its contents, along with the crucible 70, upon the centrifugal arm 42.

For this purpose the mechanism shown in Figures 1 and 2, exclusive of the crucible 50 and the flask with its contents, are brought

into the positions indicated for them in these two figures. Next the crucible 70 is fitted edgewise into the void 68 shown in Figure 3 and then the flask and crucible are together mounted upon the yoke 46, the flask being 70 secured in position upon this yoke in the manner above described. The flask with its filling, and the crucible 70, now appear as indicated in Figure 16.

A supply of gold is next placed in the 75 crucible, and heated by means of a blowpipe. At the same time, or as a separate step if the operator so desires, the flask and its contents are warmed or heated to a suitable extent. During the period while this is 80 being done, the arm 26 is locked against rotation in the manner above described so that for the time being the centrifugal arm 42 is stationary so that the crucible and flask are held rigidly in fixed positions.

The gold being melted, the operator grasps the handle 28, and by pulling the same so as to rock the arm 26 slightly away from the casing 18, causes the lug 38 to be withdrawn from the slot 39, and at the same time causes 90 the hook 31 of the leaf spring 30 to snap into the notch 29, as above explained, so that the handle 26 now occupies the position indicated for it in Figure 3.

The operator now turns the handle freely, 95 thereby causing the rotation of the gear 22, the pinion 23, the shaft 40 and the centrifugal arm 42. The molten gold is by centrifugal force carried out of the crucible 70, through the ingate 69 and into the mold cavity 66. The molten metal completely fills the cavity 66 and in so doing drives out the air previously contained in the mold cavity, this air passing upwardly through the passages 67 and making its escape from the top 100 of the filling. The form of the edge portions 58, indicated in Figure 8, facilitate the escape of the air from the flask. The molten metal rises in the passages 67, and thus forms gold wires of threads which are subsequently cut off, as above described, so as to leave the projecting portions 73. The step just described is of course performed after 105 the casting is completed and removed from the filling.

As soon as the molten metal within the mold has cooled sufficiently to render it rigid, the operator stops turning the handle 28, and thus brings the various revoluble parts to a standstill. He locks the arm 26 against rotation, by causing the lug 38 to be thrust into the slot 39, in the manner above described. This leaves the various revoluble parts in the positions they occupied respectively at the start.

The operator now disconnects the flask from the yoke 46, by withdrawing the hook 51 from the hole 51^a so as to release the anchoring rib 45 of the flask. This done, 125 the flask is taken off by merely sliding it in 130

the general direction of the length of the centrifugal arm 42.

This leaves the machine in condition for the operator to proceed with the work of 5 making another casting.

While the rotation of the revoluble parts may be in either of two directions, I prefer to rotate them so that the arm 26 turns in a clockwise direction, the revoluble parts thus 10 turning in the direction indicated for them by the arrows.

I do not limit myself to any particular proportion or sizes for the various parts of 15 my device nor to any special material to be employed in the construction thereof, nor to any particular use for which the device may be employed. While well adapted for castings used in connection with dentures, my apparatus may be employed with equal 20 facility for making castings of other kinds, and which may be either large or small.

The castings produced may be made of any metal or other fusible or moldable material adapted for being made into castings.

25 Having thus described my invention, what I claim as new and desire to secure by Letters Patent is as follows:

1. A rotary casting device, comprising a 30 centrifugal arm, means for turning the same, a flask mounted upon said arm and revoluble therewith, a filling contained within said flask and provided with a mold cavity and with an ingate communicating with said mold cavity, and a crucible supported by 35 said centrifugal arm and extending into said flask and into close proximity to said ingate, for the purpose of delivering moldable material thereinto, said crucible resting against said filling so as to press thereupon when 40 the cylindrical arm is rotated.

2. A rotary casting device, comprising a 45 centrifugal arm, means for turning the same, a flask carried by said centrifugal arm, a filling carried by said flask, and a crucible carried by said centrifugal arm, said crucible being provided with a portion 50 extending into said flask and resting against said filling for the purpose of delivering molten metal or the like into a filling carried by said flask.

3. A rotary casting device, comprising a 55 centrifugal member, means for turning the same, a flask carried by said centrifugal member, a mold filling carried by said flask and provided with a mold cavity and an ingate leading to said mold cavity, said mold filling being further provided with an indentation located in proximity to said 60 ingate, and a crucible carried by said centrifugal member and fitting into said indentation in said filling, for the purpose of delivering molten metal or the like into said ingate.

4. A rotary casting device, comprising a 65 centrifugally operated supporting member, means for actuating the same, a flask mount-

ed upon said centrifugally operated supporting member, a filling carried by said flask and provided with a mold cavity and with an ingate communicating with said mold cavity, and a receptacle carried by said 70 centrifugally operated supporting member and detachably engaging said filling at a point in close proximity to said ingate, for the purpose of discharging a moldable material into said ingate.

5. A rotary casting device, comprising a 75 centrifugal arm, a yoke mounted thereupon and provided with a projecting portion, a crucible carried by said yoke and engaging said projecting portion, a flask mounted 80 upon said yoke, a filling contained within said flask and provided with a mold cavity and with an ingate communicating with said mold cavity, said filling engaging said crucible upon the side thereof opposite said projecting portion of said yoke, so that said crucible is held in position by said filling and said projecting portion, said crucible extending into said filling and into immediate proximity to said ingate, for the purpose of delivering molten metal or the like 85 thereinto.

6. A rotary casting device, comprising a 90 centrifugal arm, means for turning the same, a flask mounted upon said centrifugal arm, a filling contained within said flask and provided with a mold cavity and with an ingate communicating with said mold cavity, said filling being made of plaster of Paris, and a crucible carried by said 95 centrifugal arm and engaging said filling so that said filling braces said crucible on one side thereof, mechanism for bracing said crucible on another side thereof so as to hold said crucible rigid relatively to said 100 filling, said crucible being so located as to extend into immediate proximity to said ingate in order to deliver molten metal or the like 105 into said ingate.

7. A rotary casting device, comprising a 110 centrifugal arm, means for turning the same, a flask mounted upon said centrifugal arm, a filling contained within said flask and provided with a mold cavity and with an ingate communicating with said mold 115 cavity, said filling being further provided with an indentation merging into said ingate and a crucible carried by said centrifugal arm and fitting into said indentation, so that a portion of said crucible extends into 120 immediate proximity to said ingate, for the purpose of delivering molten metal or the like thereinto.

8. In a rotary casting device, the combination of a centrifugal arm, means for 125 turning the same, a yoke mounted upon said centrifugal arm and provided with a pair of blades separated by a slot, a flask detachably engaging said yoke and provided with a rib extending through said slot and 130

with a hole extending through said rib, and a fastening member mounted upon said yoke and provided with a portion to be thrust through said hole in said rib, for the purpose of holding said flask in position upon said centrifugal arm.

9. In a rotary casting device, the combination of a centrifugal arm, a mold mounted thereupon and revoluble therewith, gearing for turning said revoluble arm, and mechanism controllable at the will of the operator for locking said gearing in order to prevent accidental rotation of said centrifugal arm.

10. In a rotary casting device, the combination of a centrifugal arm, a molding flask mounted thereupon, gearing for turning said centrifugal arm, said gearing including a manually operated arm, a casing for supporting said gearing, and mechanism

controllable at the will of the operator for locking said manually operated arm in a predetermined position relatively to said casing.

11. In a rotary casing device, the combination of a centrifugal arm, a molding flask mounted upon said centrifugal arm, gearing connected with said centrifugal arm for turning the same, said gearing including a manually operated arm, a casing for holding said gearing, said casing being provided with a notch and said arm being provided with a lug for fitting into said notch and means controllable at the will of the operator for shifting said arm into either of two normal positions, for enabling said lug to enter said notch, or for preventing said lug from entering said notch.

GEORGE A. WIECHERT.
